UNITED STATES PATENT OFFICE.

ENOCH J. BRADY, OF BURKBURNETT, TEXAS.

WATER-MOTOR.

1,388,018.

Specification of Letters Patent. Patented Aug. 16, 1921.

Application filed November 19, 1919. Serial No. 339,072.

To all whom it may concern:

Be it known that I, ENOCH J. BRADY, a citizen of the United States, residing at Burkburnett, in the county of Wichita and State of Texas, have invented certain new and useful Improvements in Water-Motors; and I do hereby declare the following to be a full, clear, and exact description of the invention, such as will enable others skilled in the art to which it appertains to make and use the same.

This invention relates to new and useful improvements in water motors and has for one of its objects the provision of a pipe or casing placed level and having a spiral throughout its length so that a pressure of water will be exerted on the spiral throughout the entire length of the casing or pipe thereby giving an increased amount of power from the same quantity of water and which will render a double amount of power or driving force from a certain volume of water than can be obtained from any other wheel on the market or in use.

Another object of this invention is the provision of a water motor of the above stated character, which shall be simple, durable, and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following description and accompanying drawing, in which:

Figure 1 is a vertical sectional view of a water motor constructed in accordance with my invention.

Fig. 2 is a detail sectional view of a coupling for connecting the sections of the spiral together.

Fig. 3 is a front elevation of a forebay illustrating a gate thereon for controlling the inlet opening to the motor.

Referring in detail to the drawing the numeral 1 indicates a tubular casing and which may consist of a plurality of sections, but in this instance I have elected to show

a pair of sections 2 and 3 respectively. The section 3 has its forward end disposed in an inlet opening 4 of a forebay 5 and secured into said opening by means of an integral collar 6 detachably secured to the forebay by means of fasteners or bolts 7. The forebay 5 is adapted to be located within a stream of water or any other body of water so that the water can enter the section 3 of the casing 1. The forebay 5 is provided with a slidable gate 8 for the purpose of controlling the water through the inlet opening 4.

The adjacent ends of the sections 2 and 3 have annular flanges 9 formed thereon which abut each other and are detachably connected by bolts or like fasteners 10. The other end of the section 2 has formed thereon a downwardly depending discharge pipe 11 which is disposed in a plane below the inlet opening 4 so that the water in the casing after passing the full length thereof can readily flow from said casing. The forward end of the section 3 is provided with a supporting element 12 which has a bearing to support one end of a sectional spiral 13. A similar supporting member 14 is secured between the flanges 9 by the bolts or fasteners 10 and is equipped with a bearing 15 that receives a coupling 17 that detachably connects the sections of the spiral 13 together. The spiral extends the full length of the casing 1 and the section 2 is provided with an opening to permit the shaft 18 of the spiral to extend therethrough. The shaft 18 has its end journaled in a bearing 19 located in a supporter abutment 20. A power take-off wheel 21 is secured to the shaft to which machinery and the like may be connected by an endless belt. The adjacent ends of the spiral are screw threaded or the shaft portions thereof and are detachably connected by a sleeve which is internally screw threaded and indicated by the character 17.

Thus it will be seen that the spiral extending the full length of the casing 1 will receive pressure thereon throughout the entire length of the casing from the water passing through said casing.

While I have shown and described the preferred embodiment of my invention, it will be understood that minor changes in construction, combination, and arrangement

of parts may be made without departing from the spirit and scope of the invention as claimed.

Having thus described my invention what 5 I claim is:—

A water motor comprising a tube having an offset discharge portion, a bearing spaced from and opposite to the offset discharge portion, a water driven power element in the 10 tube projecting through and journaled in said offset discharge portion, said element also being journaled in said bearing, and a power take-off means on the element intermediate the offset discharge portion and

said bearing, said tube being in sections, a 15 bearing disposed intermediate said sections, securing means common to the second bearing and said sections, a coupling journaled in the second bearing, and said power element being made in sections and coupled by 20 said coupling member.

In testimony whereof I affix my signature in presence of two witnesses.

ENOCH J. BRADY.
